UNITED STATES PATENT OFFICE

HARRY P. TROENDLY, OF CHICAGO, ILLINOIS, ASSIGNOR TO PARVA PRODUCTS COMPANY, OF WILMINGTON, DELAWARE, A CORPORATION OF DELAWARE

FASTENER

Application filed July 28, 1930. Serial No. 471,316.

This invention relates to fasteners and has particular reference to a buckle adapted for use in the supporting of garments or the like.

The invention contemplates the provision of a buckle which will not slip and which may be easily and quickly adjusted to any length of strap.

The invention contemplates further the provision of a buckle which will find particular utility when used in connection with the strap of an overall and which, when so used, will be positioned close to the overall bib to thus eliminate the necessity of having a hard metal slide or the like on the overall strap adjacent the shoulder of the wearer.

The invention further contemplates the provision of a buckle which will be equally well adapted for connection to a button or a buttonhole and with which the strap may be connected by a simple threading operation.

The buckle constructed in accordance with the teachings of this invention will be simple in construction, capable of economical production on a commercial scale, and may be produced without welding.

The above and many other objects and advantages of the present invention will become more apparent as the following description proceeds, particularly when reference is had to the accompanying drawing wherein:

Figure 1 is an elevational view of a buckle constructed in accordance with the teachings of this invention;

Figure 2 is a sectional view taken substantially on the line 2—2 of Figure 1 and showing a strap connected to the buckle;

Figures 3 and 4 are elevational views showing applications of the buckle to a garment;

Figure 5 is a fragmentary elevational view of a slightly modified form of construction;

Figure 6 is a view similar to Figure 1 showing a still further modified form of construction; and

Figure 7 is a view similar to Figure 1 showing a still further modified form of construction.

Heretofore it has been customary, in order to connect the strap of an overall to the bib thereof, to form a loop in the overall strap

and to adjustably connect the free end of this loop to the body of the strap by means of a slide buckle. A wire loop member has then been slidably mounted on the loop of the strap for connection with the button formed on the overall bib. The slide for adjusting the length of the overall strap has generally been formed of wire and, in use, it has been found that this strap generally assumes a position on the top of the shoulder of the wearer.

This method of attaching an overall strap to an overall bib has not proven entirely satisfactory; first, because it has been necessary to form separate members, including the wire loop member and the adjustable slide, and second, because the hard metal slide on the shoulder of the wearer has been found to dig into the flesh when a heavy load is lifted. The present invention contemplates the elimination of these disadvantages by providing a loop member and slide formed as a single unit which, in use, will be positioned at the point of connection between the overall strap and the overall bib. The invention further contemplates the provision of a combined slide and loop member which may be stamped from substantially flat material so that the necessity of welding the ends of the wire, as was necessary in the formation of wire buckles, is eliminated.

Broadly, the invention comprises a stamping having a portion adapted for adjustable connection to a strap and having a second portion adapted for connection with a button or with the material adjacent a buttonhole. Several embodiments of the inventive idea are disclosed in the drawing, and, by reference to the figures thereof, it will be noted that the buckle may comprise a metal stamping designated generally by the reference character 10. In its preferred form, the stamping provides a frame having the upper and lower sides 11 and 12, respectively, and the ends 13 and 14. Integrally connected with this frame by a neck 15 is a loop member 16 which, as illustrated, may preferably be clover leaf shaped to provide the opening 17 for a purpose hereinafter to be more fully described.

Stamped integral with the sides 13 and 14 are bars 18 and 19, the latter being provided with portions 20 offset in the direction of the side 12 of the frame. These bars provide members about which an overall strap, such as designated by the reference character 21 in Figure 2 of the drawing, may be threaded to adjustably connect the buckle to the strap. Thus, as illustrated, the strap may be threaded under the side 11, over the bars 18 and 19, then upwardly around the bar 19 and in back of the bar 18, after which the free end of the strap may be permitted to hang downwardly in the position shown in Figure 2. When the strap is thus threaded in the frame, it will be found that the strap will be firmly but adjustably connected to the frame.

The loop member 16 is, as brought out before, provided with the opening 17 for engagement with a button 25, as clearly illustrated in Figure 3 of the drawing. Thus, the button fixed to the bib 26 may be inserted through the portion of the opening 17 and the buckle may then be moved to position the button over the reduced portion of the opening 17 with the result that the button may not become accidentally disengaged from the loop member. With the loop member connected to a button and with the frame adjustably connected to the overall strap, it will be found that, as illustrated in Figure 3 of the drawing, the frame will be adjacent the bib 26 with the free end of the overall strap behind the bib.

The loop member is equally well adapted for engagement with the material adjacent a buttonhole, as illustrated in Figure 4 of the drawing. Thus, the loop member is provided with the portions 27 and 28, which extend at substantially right angles to the neck 15 and parallel to the side 12 of the frame, these portions thus being adapted for hooking engagement with the material adjacent a buttonhole 29. With the loop member engaged in a buttonhole in the manner illustrated, it will be found that the buckle will again be located adjacent the bib of the overall where it is readily accessible for adjustment and that the free end of the overall strap will lie behind the overall bib.

In Figure 5 a slightly modified form of construction is disclosed in which there is substituted for the loop member a member 35 which is adapted only for engagement with the material adjacent a buttonhole. This member may be stamped integral with the frame from flat sheet material and may be connected to the base 12' of the frame by a neck 15'. The member 35 is, of course, provided with the portions 36 and 37 which extend at substantially right angles to the neck 15' and parallel to the side 12' of the frame for hooking engagement with the material adjacent a buttonhole.

In Figure 6 a further modification of the

inventive idea is disclosed in which the bar 19' of the buckle is provided with the serrated edge 38 which, as illustrated, may be directed toward the side 12'' of the frame. In other respects, this buckle is similar to the buckle shown in Figure 1 and is adapted for use in the same manner.

In Figure 7 a further modified form of construction is shown and by reference to this figure it will be noted that the fastener may include the frame 10' having the upper and lower sides 11' and 12' respectively. In this form of construction, however, the loop member 16' is not adapted for engagement with the material adjacent a buttonhole but is only adapted for engagement with a button or the like. Thus the neck 15 is eliminated and the base 50 of the loop member 16' is formed integral with and merges into the lower side 12' of the frame. The loop member 16' is provided with the opening 17' which, as illustrated, may be, if desired, substantially clover leaf shaped, while the frame is provided with the cross bars 18' and 19' to permit adjustable connection of the frame to a strap. Thus this form of construction provides a frame adapted for adjustable connection to a strap and a loop member having its one side formed integral with one side of the frame, this loop member being adapted for engagement with a button.

In each of the modifications disclosed, it will be noted that the buckle may be formed by stamping the same as a unit from flat sheet material such as metal. The buckle may thus be economically manufactured and since all of the portions of the stamping may be formed to lie in a single plane, the buckle will be extremely flat and will thus lie closely adjacent the body of the wearer. The strap may be readily adjusted on the buckle and the portion of the buckle which is adjustably connected to the strap will be adjacent the upper edge of the bib of the overall and thus will not be in a position to bite into the shoulder of the wearer.

While the invention has been described with considerable detail, it is to be clearly understood that the description is for the purposes of illustration only and is not definitive of the limits of the inventive idea. The right is therefore reserved to make such changes in the details of construction and arrangement of parts as will fall within the purview of the attached claims.

What I claim as my invention is:

1. A new article of manufacture comprising a sheet metal stamping shaped to define a frame, spaced bars connecting opposite sides of said frame, a clover leaf shaped loop, and a connection between said loop and said frame, one of said bars being provided with rounded offset portions arranged in the plane of said frame.

2. A new article of manufacture compris-

ing a frame having spaced ends, a bar connecting the spaced ends of said frame, blunt offset portions on said bar, said offset portions being spaced a substantial distance apart and extending in the same direction from said bar, and means free from clamping co-action with said bar and cooperating with said frame for holding a strap folded around said bar with the portions of the strap on opposite sides of the line of fold thereof extending in substantially the same direction from said bar, the offset portions on the bar being adapted to engage the line of fold of the strap upon the exertion of a relative pull between the strap and frame longitudinally of the strap, the spacing of the offset portions providing for a transverse distortion of the strap against the direction of pull.

3. A new article of manufacture comprising a frame having spaced ends, a bar connecting the spaced ends of said frame, blunt offset portions on said bar, said offset portions being spaced a substantial distance apart and extending in the same direction from said bar, and means including a second bar free from clamping co-action with said first-mentioned bar and connecting the spaced ends of said frame for holding a strap folded around said first mentioned bar with the portions of the strap on opposite sides of the line of fold thereof extending in substantially the same direction from said bar, the offset portions on the first mentioned bar being adapted to engage the line of fold of the strap upon the exertion of a relative pull between the strap and frame longitudinally of the strap, the spacing of the offset portions providing for a transverse distortion of the strap against the direction of pull.

4. A new article of manufacture comprising a frame having a loop extending from one side thereof, a bar connecting opposite ends of said frame and extending substantially parallel with the said loop side, blunt offset portions on said bar, said offset portions being spaced a substantial distance apart and extending from said bar in the direction of the loop side of the frame, and means free from clamping co-action with said bar and cooperating with said frame for holding a strap folded around said bar in such a manner that the offset portions on the bar will engage the line of fold of the strap upon the exertion of a relative pull between the strap and frame longitudinally of the strap, the spacing of said offset portions providing for a transverse distortion of the strap against the direction of pull.

5. A new article of manufacture comprising a frame having upper and lower side bars and end bars connecting said side bars, upper and lower intermediate bars connecting said end bars and dividing the interior of said frame into upper, lower and intermediate slots, and blunt offset portions on

said lower intermediate bar, said offset portions being spaced a substantial distance apart and extending from said bar in the direction of the lower side bar of the frame, the arrangement being such that a strap folded around said lower intermediate bar and having portions on opposite sides of its line of fold threaded through said upper slot will have its line of fold engaged by the offset portions on the lower intermediate bar upon the exertion of a relative pull between the strap and frame longitudinally of the strap, the offset portions on said lower intermediate bar being sufficiently rigid and the spacing thereof being such as to provide for a transverse distortion of the strap against the direction of pull.

6. A new article of manufacture comprising a frame having upper and lower side bars and end bars connecting said side bars, upper and lower intermediate bars free from clamping co-action with each other and connecting said end bars and dividing the interior of said frame into upper, lower and intermediate slots, a loop extending from the lower side bar of said frame, and blunt offset portions on said lower intermediate bar, said offset portions being spaced a substantial distance apart and extending from said bar in the direction of the lower side bar of the frame, the arrangement being such that a strap so threaded through said slots as to be held in folded position about said lower intermediate bar will have its line of fold engaged by the said offset portions upon the exertion of a relative pull between the strap and frame longitudinally of the strap, the spacing of the offset portions providing for a transverse distortion of the strap against the direction of pull.

7. A new article of manufacture comprising a sheet metal stamping shaped to define a frame having upper and lower side bars and end bars connecting said side bars, upper and lower intermediate bars integrally connecting said end bars and dividing the interior of said frame into upper, lower and intermediate slots, a loop formed integral with the lower side bar of said frame, and blunt offset portions on said lower intermediate bar, said offset portions being spaced a substantial distance apart and extending from said bar in the direction of the lower side bar of the frame, the arrangement being such that a strap so threaded through said slots as to be held in folded position about said lower intermediate bar will have its line of fold engaged by the said offset portions upon the exertion of a relative pull between the strap and frame longitudinally of the strap, the spacing of the offset portions providing for a transverse distortion of the strap against the direction of pull.

In testimony whereof I affix my signature.
HARRY P. TROENDLY.
